UNITED STATES PATENT OFFICE.

EDWIN E. FREDERICK, OF BELLEVUE, PENNSYLVANIA, ASSIGNEE TO THE FREDERICK-ELDER CO., INC., OF PITTSBURG, PENNSYLVANIA.

SWITCH-OPERATING MECHANISM.

No. 873,741.

Specification of Letters Patent.

Patented Dec. 17, 1907.

Application filed April 12, 1906. Serial No. 311,324.

To all whom it may concern:

Be it known that I, EDWIN E. FREDERICK, a citizen of the United States, residing at Bellevue, in the county of Allegheny and 5 State of Pennsylvania, have invented a new and useful Switch-Operating Mechanism, of which the following is a specification.

This invention relates more particularly to switches for opening and closing electric 10 circuits.

The primary object is to provide simple mechanism of a novel nature, whereby a single actuating device is employed for operating the switch, and successive corresponding movements in the same direction of said device will effect, alternately, the opening and closing of the switch, thus making the operation thereof exceedingly simple, and not apt to be misunderstood.

20 A further and important object is to provide a structure of the above character that can be readily installed in any of a variety of ways, and is not liable to become inoperative or deranged.

25 While the invention is undoubtedly open to various changes and modifications, the preferred embodiment thereof is illustrated in the accompanying drawings, wherein—

Figure 1 is a side elevation of the switch. 30 Fig. 2 is a vertical sectional view through the same. Fig. 3 is a perspective view of said switch with the casing removed. Fig. 4 is a top plan view. Fig. 5 is a detail view of the standard and parts associated therewith, 35 said standard being shown partially in section. Fig. 6 is a detail view, illustrating the relation of the contact elements when the switch is opened. Fig. 7 is a detail sectional view on the line 7—7 of Fig. 4.

40 Like numerals of reference designate corresponding parts in all the figures of the drawings.

In the embodiment illustrated, a base 8 is employed, which is constructed of suitable 45 insulating material, and has an upstanding annular flange 9. Within the recessed seat formed by the flange is secured a plate 10, having a central standard 11 thereon, which standard is concentric to the flange 9, and 50 has its outer portion tubular. A shaft 12 is journaled in the inner portion of the standard 11, and has secured to one end and on one side of said standard, a ratchet wheel 13. An actuating member, in the form of a plunger 14, is slidably mounted in the tubular 55

portion of the standard, and has at its outer end a push button 15, preferably of insulating material. A coiled spring 16, arranged within the tubular portion of the standard, has its outer end disposed in a socket 17 in 60 the plunger, and serves to yieldingly maintain the plunger in its outermost position. The said plunger is provided on one side with a lug 18, slidably mounted in a slot 19 in the standard, said lug having secured thereto a 65 yielding dog 20 that co-operates with the teeth of the ratchet wheel. A detent spring 21, secured to the base plate 10, also coacts with the teeth of the wheel 13 to prevent its retrograde movement. It will be apparent 70 from the above that if the plunger 14 is reciprocated, the wheel 13 and the shaft 12 to which it is secured will be given a step by step rotation.

Secured to the opposite end of the shaft to 75 that carrying the ratchet wheel 13, and located on the opposite side of the standard, to said ratchet wheel, is a contact member. The same comprises a supporting plate 22, which in the present embodiment, is substantially 80 triangular, but the shape may be varied. The corners of this plate have ears 23, and carried by said ears are a plurality of separate and independent contact elements or devices. These devices each comprise metallic heads 85 23^a located on opposite sides of the plate, and connected by a shank 24, as clearly shown in Fig. 2. Insulation 25 serves to maintain the various contact elements out of electrical engagement with the plate 22 supporting 90 them. The present embodiment is a double pole switch, and therefore a plurality of sets of yielding contacts coact with the above described member. As shown, these yielding contacts are in the form of spring plates 26 95 having doubled terminals 27, disposed in the paths of movement of the heads 24, and arranged in opposing relation, so that when one of the contact elements is located between a set of the springs, said springs will 100 be in electrical communication through the element. The springs are moreover so disposed that the contact devices of both sets will be connected at the same time, all of which is illustrated in Fig. 3.

105 The spring devices 26 have enlarged terminals 28 that rest upon the flange 9 of the base, and are secured thereto by binding posts 29 arranged upon the flange over the plates 28. The binding posts, as shown in 110

Fig. 7, are held by suitable screws 30, or other fasteners. The base is provided with a series of conductor-receiving openings 31 that pass through the flange, and the posts 5 have socket members 32, the openings of which are alined with the openings 31, as illustrated in Fig. 7. Holding screws 33, carried by the socket members, serve to secure the conductor wires to the binding posts. A 10 suitable casing is preferably employed for the mechanism, said casing in the present embodiment being shown as cylindrical, and being designated 34. It completely encloses the base, and is held in place by suitable screws 35 that engage in bayonet slots 36, formed in said casing. The casing is 15 preferably provided with an insulating lining 37, and has a central opening 38, through which the plunger 15 projects. It will be 20 clear that if the leads of any electric circuit are properly connected to the binding posts and the plunger is reciprocated, the rotatable contact elements will alternately move into and out of engagement with the 25 springs, thus closing and opening the circuit. There is but one operating device necessary and the movement of the same thereof is always in the same direction to both open and close the switch, thus making it exceedingly 30 simple and not readily misunderstood. The mechanism moreover is made up of simple parts that are not liable to become inoperative or deranged.

From the foregoing, it is thought that the 35 construction, operation, and many advantages of the herein described invention will be apparent to those skilled in the art, and it will be understood that various changes in the size, shape, proportion, and minor details 40 of construction, may be resorted to without departing from the spirit or sacrificing any of the advantages of the invention. For instance, the material of which the various parts are constructed may be of any desired 45 or suitable character, and while the present embodiment is a double pole switch, it will be evident that by eliminating one set of the contact springs, it may be readily changed into a single pole switch.

Having thus fully described my invention, what I claim as new, and desire to secure by Letters Patent, is:

1. In a switch of the character described, the combination with a base, of a tubular 55 standard carried thereby, a shaft journaled on the inner portion of the standard, a contact member carried by the shaft on one side of the standard, a ratchet wheel carried by the shaft on the other side of the standard, a 60 plunger slidably mounted within the standard and projecting therefrom, said standard having a slot, a dog secured to the standard and operating in the slot, said dog co-operat-

ing with the ratchet wheel to move the same, and a spring arranged within the standard 65 and engaging the plunger to yieldingly maintain the same in its outermost position.

2. In a switch of the character described, the combination with a standard having a bore in its outer portion, of a plunger slidably mounted on the bore and projecting from the outer end of the standard, a shaft 70 journaled transversely in the inner end of the standard in line with the plunger and having its axis intersecting the axis of the 75 bore, said shaft having its ends projecting on opposite sides of said standard, a contact member carried by one projecting end of the shaft on one side of the standard, and actuating means for the shaft located on the other 80 side of the standard and connected to the other projecting end of the shaft and to the plunger.

3. In a switch of the character described, the combination with a tubular standard 85 having a slot in one side provided with closed ends, of a rotary contact member, a reciprocatory plunger slidably mounted in the bore of the standard, and actuating means for the contact member including the 90 dog secured to the side of the plunger and extending through the slot of the standard, said dog having a portion abutting against the end walls of the slot and constituting means for retaining the plunger within the 95 standard and limiting the movement of said plunger.

4. In a switch of the character described, the combination with a base having an annular flange forming within it a recessed seat, 100 of a standard secured to the base within the seat and surrounded by said flange, a shaft journaled transversely on the inner portion of the standard and projecting beyond opposite sides thereof, said shaft having a ratchet 105 wheel on one projecting end, and a contact member on the other projecting end, said wheel and member being thus disposed on opposite sides of the standard and within the flange, a reciprocatory actuating plunger 110 slidably mounted on the standard and having a dog coacting with the wheel, a plurality of spring contact elements mounted on the outer face of the flange of the base and disposed in the path of movement of portions of the rotatable contact member, and binding posts secured to said flange and engaging the contact springs to hold the same in position.

In testimony, that I claim the foregoing 120 as my own, I have hereto affixed my signature in the presence of two witnesses.

EDWIN E. FREDERICK.
